UNITED STATES PATENT OFFICE.

LOUIS A. HAWTHORNE, OF NEWARK, NEW JERSEY, ASSIGNOR TO STEEL UTILITIES INCORPORATED, A CORPORATION OF NEW YORK.

CRATING APPARATUS.

1,354,250.

Specification of Letters Patent. Patented Sept. 28, 1920.

Application filed December 28, 1918. Serial No. 268,738.

To all whom it may concern:

Be it known that I, LOUIS A. HAWTHORNE, a citizen of the United States, residing at Newark, in the county of Essex and State of 5 New Jersey, have invented certain new and useful Improvements in Crating Apparatus, of which the following is a specification.

This invention relates to crating machinery, and more particularly to a novel apparatus for automatically assembling bottles or other containers and placing them in proper order in shipping crates, boxes or the like.

In the handling of containers such as bottles on a large scale, suitable apparatus for rapidly, quickly and accurately filling the numerous cells or checkers of the crates or boxes, is a very desirable auxiliary for the expeditious and economical carrying out of 20 that operation. Accordingly, the present invention has primarily in view a simple and efficient apparatus which may be advantageously and conveniently used in a bottling plant in conjunction with the other usual machinery, whereby the several containers 25 may be automatically loaded into the crates without danger of breakage or disorder.

A further object of the invention is to provide an apparatus of this type of maximum simplicity, not only as to the number 30 of parts involved, but also as to the operations necessary to assemble and deposit the containers in proper order within the crates, while the latter are automatically advanced 35 into receiving position synchronously with the operation of the depositing or transferring instrumentalities.

With the above and other objects in view which will more readily appear as the nature 40 of the invention is better understood, the same consists in the novel construction, combination, and arrangement of parts hereinafter more fully described, illustrated and claimed.

45 A preferred and practical embodiment of the invention is shown in the accompanying drawings, in which:—

Figure 1 is a side elevation, partly in section of the improved apparatus.

50 Fig. 2 is a detail vertical sectional view showing more clearly the escapement sprocket of the operating unit.

55 Fig. 3 is a top plan view, partly in section, further illustrating the operating unit and its connections.

Fig. 4 is a transverse vertical sectional

view taken substantially on the line 4—4 of Fig. 1.

Fig. 5 is a horizontal sectional view taken on the line 5—5 of Fig. 4 looking in the direction of the arrows.

Fig. 6 is a detail view showing the means employed for connecting and disconnecting the shaft of the operating unit with the source of power.

Fig. 7 is a detail view partly in elevation and partly in section showing the construction of the device shown in Fig. 6.

Fig. 8 is a vertical sectional view taken on the line 8—8 of Fig. 5.

Similar reference characters designate corresponding parts throughout the several figures of the drawings.

In carrying forward the general object of the invention, namely that of rapidly and expeditiously filling the cells or checkers of a crate, it is proposed to provide an apparatus including means for assembling a number of containers in a group, the said containers having a spaced relation corresponding to that of the compartments in the crate, and means for bodily transferring the group of containers thus assembled into the crate. That is to say, it is proposed in the general lay-out of the invention to provide a bottle 85 collecting station S preferably located above a suitable crate feeding guide-way G, at which station the bottles or other containers are received from the labeling machine or other device which may have handled the 90 containers just preceding the packaging operation.

For the purpose of removing the containers from the collecting station S and transferring or depositing the same into the crate 95 C traveling therebelow in the guide-way G, there is preferably located at said station a novel transfer device A which is adapted to co-operate with a placing device B for displacing the collected and assembled bottles 100 into engagement with the transfer device from which they are ultimately deposited in proper order into the crates.

The transfer device A and placing device B have suitable actuating connections with 105 an operating unit designated generally as D arranged at one end of the frame F, and as will hereinafter more fully appear, the operation of said devices A and B is controlled entirely by the bottles or other containers 110 collected at the station S.

The foregoing gives the general plan and

functional idea of the machine, and now referring more specifically to the detail structural features and essential characteristics of the apparatus embodying the foregoing units, it will be observed that the frame F is provided with a suitable intermediate upright portion 1 having thereon a flat top or table surface 2 whose edge 3 is substantially in the same plane as one of the walls of a container feeding guide-way 4 through which the containers may be conveyed on a suitable belt 5 or equivalent conveyer and deposited onto the table 2 in successive order. This table 2 and its related instrumentalities constitute the collecting station S previously referred to. At one edge thereof operates the transfer device A which essentially consists of a vertically movable transferring head designated generally as H which is adapted to receive the containers from the table 2 when the pusher plate 6 of the placing device B is shifted across the container receiving zone of the collecting station.

The said transferring head H includes a container positioning rest 7 consisting of a series of adjoining receiving pockets 8 with intermediate guiding tongues 8^a separating the pockets and serving to deflect and guide the bottles into the pockets when pushed therein by the placing device. In the present embodiment four bottle separating and holding pockets 8 are shown, and above these pockets is located a holding rack having associated therewith gripping means adapted to hold the containers until they are properly directed to a position for deposit in the checkers of the crate, and to then release the same to permit them to gently drop into final position.

As the present machine is illustrated particularly in its application to the handling of bottles it will be observed from Figs. 3 and 4 of the drawings that the said means for engaging the necks of the containers essentially consists of a rack plate 9, having a plurality of relatively narrow slots 10 for receiving the necks of the bottles, and also provided at one edge portion of each slot with a spring-pressed holding detent 11. Each detent has a substantially hook-shaped end coöoperating with the adjacent slot to grip the neck of a bottle and prevent its displacement until the proper time. All of the said detents 11 are adapted to be simultaneously engaged by the upstanding lugs 12 of a common releasing bar 13, each of which lugs engages with the tail of a detent when the bar 13 is shifted longitudinally to release the forward engaging ends or hooks of the detents from gripping engagement with the bottle necks.

The transferring head H of the device A also includes the opposite vertically disposed supporting carrier rods 14 which are suit-

ably guided in the frame F whereby the entire head may be lowered from the collecting station level into the crates C fed therebeneath. As will be observed from Figs. 1 and 4, the rods 14 are fitted with the studs 15 which are adapted to be respectively engaged by the slotted ends of suitable motion-transmitting levers 16 and 17 which are rigidly carried by a shaft 18 journaled in the opposite side walls of the frame F. 70 One of the said levers, namely the lever 16, is provided with a downwardly projecting slotted arm 19 which is adapted to engage with a roller 20 projecting laterally from a slide bar 21 mounted to reciprocate in an 80 inclined guide-way 22 formed in one of the side walls of the frame F. This slide bar 21 carries at the end opposite its connection with the lever 16 another laterally offset roller 23 which is adapted to ride in the cam 85 groove 24 of a cam disk 25 mounted upon the main actuating shaft 26 of the operating unit D. The formation of the groove 24 in the cam disk 25 is such that the initial movement of the disk 25 will slightly lower the 90 entire transferring head whereby the threshold portion of the rest 7 leading to the pockets 8 will register flush with the table surface 2 whereby the bottles may be conveniently placed into the head by the operation of the pusher plate 6 of the placing device. Then, as the cam disk continues in its movement, the slide bar 21 will be pulled to the right in the guide-way 22 and thus cause the rocking of the shaft 18 through the slot 100 and roller connections 19 and 20, whereby both arms 16 and 17 which are connected with the supporting rods 14 will swing downwardly and cause the transferring head to lower the bottles held thereby into crating 105 position.

It will be observed that the general dimensions and structural characteristics of the transferring head H are such that the same may be conveniently lowered into the crate 110 as far as the top of the checkers. When the head has reached this limit of movement, the beveled end 13^a of the releasing bar 13 will strike against the bevel end of the stationary abutment 13^b to cause the entire bar to be 115 shifted laterally and actuate all of the spring-pressed detents or keeper members 11 which grip the neck of the bottle. This action releases the bottles and permits the same to gently slide through the separating and guiding pockets 8 into the cells or checkers of the crate. After the bottles have thus been deposited, the continued rotation of the cam disk 25 will cause the slide bar 21 to return to its normal position and consequently the transferring head H will thereby be elevated to its original position at the collecting station.

The placing device B which coöperates with the transferring head to displace bot- 130

bles from the receiving zone of the collecting station to the said head includes in its organization, as previously indicated, the pusher plate 6 which not only sweeps across the bottle receiving zone to place the bottles in the transferring head, but at the same time acts as a wall or guide for assisting the proper alignment of the bottles on the table or platform 2. As will be observed from Fig. 3 it constitutes in effect a continuation of one of the walls of the guide-way 4 when in its normal position, and thus effectively coöperates with the slightly elevated edge 7^a of the rest 7 to compel the proper arrangement of bottles in front of the receiving rack. The said pusher plate 6 has connected therewith suitable operating instrumentalities, which as will hereinafter more fully appear, are timed or synchronized to operate at proper intervals to cause the displacing of the group of containers from the collecting station into the transferring head. By reference to Figs. 1 and 3 it will be observed that these instrumentalities consist in the present instance of a pair of relatively long levers 27 and 28 connected at their upper ends by means of links L, directly with the pusher plate 6 while their lower ends are mounted upon a transverse shaft 29 journaled in the opposite side walls of the frame. As seen in Fig. 4, one of these levers, namely the lever 28, is provided with an extension 30 whose lower end is slotted as at 31 and receives a roller 32 carried upon a slide bar 33 mounted in an inclined guide-way 34 similar in all respects to the guide-way 22 and slide bar 21 on the opposite side wall of the frame. This slide bar 33 is also provided at the end opposite the roller 32 with another roller 35 which is adapted to ride in the cam slot 36 of a cam disk 37 rigidly carried by the actuating shaft 26 of the operating unit D. Obviously the rotation of the shaft 26 will cause a corresponding rotation of the disk 37 and will move the slide bar 33, thus causing the shaft 29 carrying the lever arms 27 and 28 to rock and move the pusher plate 6.

The operating unit D above referred to includes in addition to the shaft 26 and cam disks 25 and 37, an intermediate crate advancing and feeding unit which provides for intermittently advancing the crates C step-by-step to bring the parallel rows of checkers in exact position to receive bottles from the transferring head H. In Fig. 3 this unit is shown as preferably consisting of a friction disk 38 keyed to shaft 36 and having a hub portion 39 which is adapted to loosely receive a sprocket wheel 40 having suitable radially projecting conveyer advancing teeth 41 and laterally projecting escapement teeth 42. This wheel 40 is held frictionally engaged with the disk 38 fast on the shaft 26 by means of the friction presser

disk 43 and springs 43^x, it being noted that the friction disk 43 is slidably mounted on the hub or sleeve 39 of the disk 38 so that the sprocket is frictionally clamped between the two disks. Therefore, under normal conditions when the shaft 26 is rotated the teeth 41 of the sprocket wheel will engage with the links of the conveyer chain α to properly advance the crates in the guide-way G. For the purpose of insuring only a definite predetermined movement for the crates, corresponding to each actuation of the head H, there is provided a trip shaft 43^a carrying at its intermediate portion an escapement dog 44 which is adapted to engage with laterally projecting teeth 42 of the sprocket 40 to arrest its movement at the proper time. This shaft 43^a is journaled in the opposite side walls of the frame F, and is normally rocked by a spring 45 in such a direction that the dog 44 will be in a position to engage one of the teeth 42. This spring 45 engages with a radially projecting arm 46 carried at one end of the shaft 43^a (see Fig. 1) and fastens to the frame or other fixed point of connection. The opposite end of the shaft 43^a carries therewith a radially projecting tripping arm 47 which is adapted to be engaged by a laterally projecting pin 48 carried by the cam disk 25. The effect of the engagement of the pin 48 with the arm 47 is, when the disk 25 moves, to rock the shaft 43^a against the tension of the spring 45 to release the hook end of the dog 44 from engagement with one of the escapement teeth 42. In this connection it will be noted that the pin 48 is normally in such a position that the first movement of the shaft 26 will cause it to engage with the arm 47 to rock the shaft 43^a, and thus release the sprocket 40 so that the movement of the shaft 26 will cause the same to advance one of the crates until the hooked end of the dog engages with the next escapement tooth. Obviously, the rotation of the cam disk 25 and also the cam disk 37 which are fixed on the shaft 26 will continue to perform the functions of operating the pusher plate and also the transferring head, after the movement of the sprocket 40 has been arrested by the dog 44. The friction mounting of the sprocket wheel 40, of course, readily permits of this action taking place.

Referring further to the operating unit D it will be observed from Fig. 3 of the drawing that the shaft 26 has fitted to one end thereof a combined driving and automatic clutch arrangement which includes a bevel gear 49, loose on the shaft and having a ratchet hub 50 receiving a collar 51 keyed on the shaft 26 and including a bracket arm 52 for supporting a spring pressed latch member 53 having an angularly disposed head portion 54 for engaging with the detent end of a suitable con-

trol rod 55 which constitutes a part of a container-actuated stop-motion device to be presently referred to.

The bevel gear 49 engages a beveled pinion 49^a carried upon a shaft 49^b having a chain and sprocket connection 49^c with the driving means for the container feeding conveyer 5. Thus, it will be apparent that power for driving the shaft 26 is derived through the shaft 49^b from the same means which operates the container conveyer leading from the labeling or other machine to the present crating apparatus. And, for the purpose of actuating the shaft 26 only at the desired intervals, namely when the operation of pushing the bottles into the transferring head, lowering the latter, and then advancing the crate for the next load the container actuated control or stop-motion device comes into play to release the latch 53 to permit it to engage with the ratchet hub 50 of the gear 49 which is loose on the shaft 26. Thus, the construction is such that when the pawl end of the latch 53 engages with the ratchet hub 50 through the release of the latch by the withdrawal of the member 55 from engagement with the head 54 thereof, the bevel gear 49 and shaft 26 will be directly connected to rotate together. Then, after the shaft 26 has made its cycle the angular end 54 of the latch 53 will again engage with the member 55 to withdraw the pawl end of the latch from engagement with the ratchet hub 50 and thus stop the rotation of the shaft 26.

Referring now more particularly to the member 55, which as previously indicated, is a part of a container-actuated control or stop-motion device, it will be observed more particularly from Fig. 4 that the said member 55 is a rod which is pivotally connected to the arms 56 and 57, respectively carried by the opposite side walls of the frame F, and the latter arm (57) being connected with a shaft 58 which is connected with a relatively long lever 59 carrying at its upper end a container-actuated rod 60 which projects through the stop wall 61 located at one side of the table or platform 2, whereby its free end may be readily engaged by the containers pushed into the receiving zone of the collecting station. For the purpose of maintaining the lever 59 and its associated members in proper and actual position a spring 62 may be utilized. (See Figs. 3 and 4.)

From the foregoing it will be apparent that the present apparatus provides for receiving the bottles or containers direct from the labeling or like apparatus onto the platform 2, between the edge of the rest element 7 of the transferring head and the vertical pusher plate 6 of the placing device, and when a sufficient number of containers have been pushed onto the platform or table 2,

the foremost one of the group will engage with the end of the rod 60 of the container-control device, and thus through the connections previously described will cause the rod 55 to be shifted whereby the end thereof will be disengaged from the angularly disposed portion 54 of the latch 53. Since the bevel gear 49 is continuously driven, the pawl end of the latch 53 when engaged with the ratchet hub 50 of the gear 49 will cause the shaft 26 to rotate. This rotation of the shaft will first cause the pin 48 to engage the arm 47 to rock the shaft 43^a to disengage the dog 44 from the particular escape- ment tooth with which it is engaged, where- by the sprocket wheel 40 will cause the crate conveyer to advance a crate the distance of one row of checkers to bring the empty row into position to receive the unit of bottles to be placed therein by the feeding head of the transfer device. After the crate is in position the continued movement of the shaft 26 will not affect the position of the crate owing to the friction clutch arrangement previously indicated in connection with the sprocket 40, but the cam disks 25 and 37 will cause the operation of the slide bars 21 and 33 to respectively operate the pusher plate 6 of the placing device to sweep the bottles into the rack of the feed- ing head, and then lower the transferring head with the bottles into the crate where they will be released at the downward limit of movement of the head through the engagement of the releasing bar 12 with the bevel abutment 13^b.

A feature of practical importance in connection with the operation of the present machine is that of having the crate guide-way inclined as at y where it directs the crates onto the horizontal part of the guide-way beneath the bottle collecting and transferring station. By reason of this arrangement the crates will feed downward from an incline so that as they enter the machine their top edges only will be in contact. The practical effect of thus feeding the crates with their top edges only in contact is to leave a very substantial separation between the bottom edges of the crate at the point where the conveyer projections or lugs x' engage with the end of the crate to be advanced step by step beneath the collecting and transfer station. In this connection it will also be noted that by reason of leaving ample free space for the conveyer lugs to engage with the crates there may be considerable variations in the length of the crates due to warping or other conditions, and such variations can readily be taken care of by a piece of rubber, spring or other flexible material placed on the conveyer lugs or fingers x' which will serve to hold the crates firmly between the fingers or lugs regardless of the variations in length.

Another feature of practical importance is the structural characteristic of the dropping transfer head which may be readily removed from its carrier rods and be replaced by another head to suit various shapes and sizes of containers, and likewise, the machine may be readily adapted to handle various sizes of crates by simply changing the side guides on the crate guideway 10 and the number of the lugs on the driving sprocket.

While the embodiment of the invention herein shown and described possesses special utility in its application to placing containers in a cellular shipping crate it will of course be understood that my invention is not limited to this particular use of the apparatus, since the novel instrumentalities employed by me, in the various combinations claimed, are available for use for crating purposes generally, to properly assemble bottles, cans and other containers, and place them in proper order in their shipping crates, boxes, or other packages.

25 Other practical features and advantages of the machine will be apparent to those familiar with the art, and furthermore various changes in the form, proportion and minor details of construction may be 30 sorted to without departing from the spirit or sacrificing any of the advantages of the invention.

I claim:

1. A crating apparatus including crate feeding means, a container collecting station above the crate feeding means, a transfer device for receiving the group of containers from the collecting station and holding the same therein, and an operating unit having 40 synchronized operating connections respectively with the crate feeding means and transfer device for lowering the latter toward the crate.

2. A crating apparatus including a container collecting station, means for feeding a crate beneath said station, a transfer device at one side of said station and having means for receiving and engaging containers placed therein from the collecting station and also having means for guiding the same into position in the crate, and means carried by the transfer device for releasing the containers therefrom and actuated by the return movement of the device to its 55 normal position.

3. A crating apparatus including a collecting station, means for feeding a crate beneath said station, and a transfer device arranged at one side of the collecting station 60 and having a plurality of spaced pockets for receiving the containers from the collecting station, means associated with each pocket for engaging and holding the containers, and means carried by the transfer device 65 and actuated by its movement in returning

to normal position to release the containers from the transferring head.

4. A crating apparatus including crate feeding means, a container collecting station including a stationary platform positioned above the crate feeding means and adapted to receive the containers in a line transverse to the line of crate feed, a transferring head arranged at one side of the platform of the collecting station and having container engaging and holding means, and a placing device for moving the containers from the platform of the collecting station into the receiving head, said device including a pusher plate disposed transversely to the line of crate feed and parallel to the line of container feed to the platform of the collecting station.

5. A crating apparatus including crate feeding means, a container collecting station including a stationary platform arranged above the crate feed means, a transfer device for displacing the grouped containers from the platform of the collecting station and mounted to reciprocate vertically, a device for displaying the grouped containers from the stationary platform into the transfer device, an operating unit having synchronized actuating connections respectively with the crate feeding means, transfer device, and the container displacing device, and a stop motion device operatively connected with the operating unit and tripped by the containers collected on the stationary platform of the collecting station.

6. A crating apparatus including crate feeding means, a container collecting station including a stationary platform disposed at right angles to the line of crate feed, a vertically movable transfer device also arranged at right angles to the line of crate feed and at one side of the platform of the collecting station, and having means for receiving and holding the containers, a placing device including a horizontally shiftable pusher plate arranged at the side of the platform of the station opposite the transferring head, an operating unit having operating connections with said transfer device, and said placing device, and a container-controlled stop motion device for setting the operating device in motion.

7. A crating apparatus including a station having means for assembling a number of containers into a group, means for feeding a crate beneath said station, a transfer device arranged at one side of the assembling station and including a transferring head consisting of a rack having detent means for engaging and holding a plurality of containers in spaced relation, and a placing device including a pusher plate for moving the bottles from the receiving zone of the collecting station into the rack of the transferring head.

8. A crating apparatus including a collecting station having means for assembling a number of containers into a group, means for feeding a crate beneath said station and a transfer device arranged at one side of said station, said transfer device consisting of a pair of vertically movable rods, a rack carried by the upper end of said rods and including an upper holding plate having a plurality of openings and spring-pressed detents coöperating with said openings, and a lower plate having a plurality of guide recesses for receiving the lower part of the containers, a detent operating bar associated with the upper plate of the rack, an abutment for coöperating therewith to shift the same, and a placing device arranged at the side of the station opposite the transfer device and adapted to place containers from the station into the said transferring head.
9. A crating apparatus including a collecting station having means for assembling a number of containers into a group, means for feeding a crate beneath said station, a vertically movable transfer device arranged at one side of the station and adapted to transfer containers from the collecting station level to the crates therebeneath, a placing device for positioning the grouped containers in the transfer device, and an operating unit having synchronized actuating connections respectively with the crate feeding means, the transfer device and the placing device, said operating unit including a main actuating shaft, spaced cam disks for actuating the connections to the placing device and transfer device, and a friction drive unit for moving the crate feeding means.
10. A crating apparatus including a collecting station, crate feeding means, a transfer device at one side of the collecting station, a placing device at the other side thereof, a stop motion device controlled by containers at the collecting station, and an operating unit having synchronized actuating connections with the transfer device and placing device, said operating unit including an escapement unit including a sprocket wheel for engaging with the crate feeding means and having laterally projecting escapement teeth, a trip shaft, a check dog carried thereby and adapted to engage with the said escapement teeth, a spring for rocking said shaft to cause the dog to engage with said teeth, a trip arm also carried by the trip shaft, and means carried by the operating shaft for operating said trip arm to temporarily release said dog from engagement with the escapement teeth.
11. A crating apparatus including a collecting station for the containers, means for feeding a crate beneath said station and a shifttable transfer device arranged to bodily carry the containers from said station into the crate, said shifttable transfer device being provided with a rack for the containers and yielding holding means therefor.
12. A crating apparatus including a collecting station for the containers, means for feeding a crate, and a transfer device arranged to transfer a group of the containers from the station into the crate, said transfer device having automatically released clamping elements for the containers.
13. A crating apparatus including a collecting station for the containers, means for feeding a crate and a transfer device arranged to transfer the containers from the station into the crate, said transfer device including a container positioning rest and a holding rack above the rest.
14. A crating apparatus including a collecting station for the containers, means for feeding a crate, a transfer device for the containers having a container positioning rest and a holding rack above the rest, and means for automatically holding the containers in the rack and also for releasing them therefrom.
15. A crating apparatus including a collecting station, crate feeding means, a transfer device having a container rest and a holding rack, and means carried by the rack for securing and releasing the containers.
16. A crating apparatus including a collecting station, crate feeding means below the collecting station, a shifttable transfer device arranged to bodily carry the containers from the station to the crate and provided with a holding rack for the individual containers and detents for holding the same therein, and means, operative when the transfer device is lowered, for releasing said detents.
17. A crating apparatus including a collecting station, crate feeding means, a transfer device, a placing device coöordinated with the transfer device, and an operating unit including a friction escapement actuating connection for the crate feed.
18. A crating apparatus including a collecting station, crate feeding means, a transfer device, a placing device, a stop motion device controlled by the containers at the collecting station, and an operating unit which is operatively connected with the transfer, placing and stop motion devices and includes a friction escapement device for the crate feed.
